The ornamental design for a shoe toe cap, as shown and described.

DESCRIPTION

FIG. 1 is a perspective view of a shoe toe cap in accordance with my new design.

FIG. 2 is a left side view thereof;

FIG. 3 is a right side view thereof;

FIG. 4 is a top plan view thereof;

FIG. 5 is a front elevation view thereof; and,

FIG. 6 is a rear elevation view thereof.

Broken lines showing the remainder of the shoe in the figures are for illustrative purposes only and form no part of the claimed invention.

The broken lines in the drawings illustrate unclaimed elements of the toe cap.
